GEORGE F. HALL, OF NEWARK, NEW JERSEY, ASSIGNOR OF ONE-HALF TO GEORGE E. HILL, OF EAST ORANGE, NEW JERSEY.

COMPOUND INSTRUMENT.

1,068,124.

Specification of Letters Patent.

Patented July 22, 1913.

Application filed August 21, 1912 Serial No. 716,167

To all whom it may concern:

Be it known that I, GEORGE F. HALL, a citizen of the United States, residing at Newark, in the county of Essex and State 5 of New Jersey, have invented certain new and useful Improvements in Compound Instruments; and I do hereby declare the following to be a full, clear, and exact description of the invention, such as will enable 10 others skilled in the art to which it appertains to make and use the same, reference being had to the accompanying drawings, and to characters of reference marked thereon, which form a part of this specification. 15 The present invention relates, generally, to improvements in compound instruments, and the invention refers, more particularly, to a combined T-square, protractor, bevel and triangle, arranged so as to be capable of 20 adjustment in different angles.

The invention has for its primary object to provide a simple and easily manufactured device of the character above set forth, the same being capable of use for many purposes, such as a square and bevel, a draftsman's triangle and section lining instrument, and many like purposes.

Another object of the present invention is to provide in a device of the character described, means whereby the same can be used 30 in combination with the ordinary T-square, an example of such use being the application of the device to a T-square for producing a guide for section lining at angles not 35 embraced by the ordinary forms of triangles.

A still further object of this invention is to provide in a device of the character described, a novel and positive means which is quickly and easily operated to lock in any 40 desired adjusted relation to each other the movable or adjustable parts of the device.

Other objects of the present invention, and other uses to which it may be adapted, will be readily understood from an inspection of 45 the accompanying drawings, as well as from the following detailed description of the said invention.

The invention consists, primarily, in the novel and simple construction of compound 50 instrument hereinafter set forth, and the invention consists, furthermore, in the novel arrangements and combinations of the various parts, as well as in the details of the construction thereof, all of which will be here-

inafter more fully described in the following 55 specification and then finally embodied in the clauses of the claim which are appended to and which form an essential part of this specification.

The invention is clearly illustrated in the 60 accompanying drawings, in which:—

Figure 1 is a plan view of the novel compound instrument as applied in use with an ordinary T-square. Fig. 2 is a similar plan view, illustrating by dotted representation 65 the adjustment of the movable or adjustable part of the device. Fig. 3 is a detail transverse section of the movable or adjustable head of the device, said view being drawn on an enlarged scale. Fig. 4 is a detail bottom view of a portion of the instrument 70 illustrating the pivotal connection of said movable or adjustable head with the main body of the device, and showing the rear face of the locking means. Fig. 5 is a detail 75 longitudinal section, enlarged, of the locking means for securing the movable or adjustable head in a desired adjusted relation to the main body of the device. Fig. 6 is a plan view of a slightly modified form of 80 locking means; and Fig. 7 is a longitudinal section of the same.

Similar characters of reference are employed in all of the above described views, to indicate corresponding parts. 85

Referring now to the several figures of the said drawings, the reference-character 1 indicates the complete compound instrument made according to and embodying the principles of the present invention, the same 90 comprising a main body-portion 2 provided with a straight edge 3, and having a suitable measuring scale 4 located along said straight edge 3, said scale comprising any desirable space-divisions or graduations. 95 Extending from one end of said main body-portion 2, and preferably at an angle of forty-five degrees therefrom, is an arm 5. Pivotally-connected, by means of a pivot-stud 6, with the free end of said arm 5 is 100 an adjustable head, comprising a pair of plate-members 7 and 7', which are superimposed one above the other but spaced slightly apart from each other, by means of an intermediate block or plate 8 to which 105 said plate-members 7 and 7' are riveted or otherwise secured. Said intermediate block or plate 8 is of considerably less length than

the lengths of said plate-members, so that the intervening space between the latter, adjacent to their ends, is free or open thus permitting the said plate-members 7 and 7' 5 to straddle the said arm 5 at one end and the main body-portion 2 at the other. The free ends of said plate-members 7 and 7' which overlap said main body-portion 2, are preferably beveled or cut so as to form a 10 finder or pointer-member 9, which serves, in connection therewith a proper protractor or scale of degrees 10 arranged upon the face of said main body portion 2, to indicate the adjustment of said head in desired angles 15 with relation to said main body-portion 2 and its arm 5.

The upper plate-member 7 is provided, at its inner longitudinal edge, with an upwardly projecting longitudinal rib 11, the 20 same extending at right angles to said plate-member 7; and, in like manner, the lower plate-member 7' is also provided, at both its inner and outer longitudinal edges, with upwardly projecting longitudinal ribs 12 and 25 13 respectively, the same extending at right angles to said plate-member 7'. The respective ribs 11 and 12 serve to position the instrument on the work, when the same is used, for example as a bevel, T-square or the 30 like, and the rib 13 serves to position the instrument against the edge of a T-square, as A in Fig. 1, when using said instrument in such connection. Furthermore, the ribs 12 and 13 projecting from the surface of 35 said plate-member 7', and being of the same height, serve to level said instrument, and hold the same above the drawing paper, or slightly spaced away from the paper, so that the body of the instrument does not 40 contact with the paper, a feature of great advantage when using the instrument as an aid in drafting section lining upon a drawing, since the work can be covered without danger of smutting, rubbing or blotting, as 45 will be readily understood.

In order to lock said head in any desired adjusted position with relation to said main body-portion 2 and said arm 5, the following novel means is provided:—The pivot-stud 6 is provided at one end with a head-piece 14 which is cupped out or concaved on its under side, as at 15, thus providing at the marginal edges of said head-piece a sharp gripping edge 16 which contacts with 50 the surface of said plate-member 7'. Said pivot-stud 6 is provided, adjacent to its free end with exterior screw-threads 17. Connected with said screw-threads 17 of said pivot-stud 6 by means of its interiorly 55 screw-threaded perforation 18 is a lock-nut member 19, the same being cupped out or concaved on its under side, as at 20, thus providing a sharp gripping edge 21 which contacts with the surface of said plate-member 60 7. Extending outwardly from said 65

lock-nut member 19 is a lever-arm 22 provided at its free end with an upturned finger-piece 23 whereby said arm 22 may be manipulated to tighten or loosen said lock-nut member. To adjust said head, said lever-arm 22 is moved in one direction 70 whereby said lock-nut member 19 is turned upon said screw-thread 17 of said pivot-stud 6 to loosen the same. The said head is then swung upon said pivot-stud into the 75 desired position, whereupon said lever-arm is moved in an opposite direction, tightening said nut-lock member 19 and causing the respective separated plate-members 7 and 7' to be engaged by the gripping edges 16 80 and 21 of the respective parts 14 and 19, thereby forcing into frictional or binding engagement with the opposite sides of said arm 5, the respective plate-members 7 and 7', the said gripping edges 16 and 21 by 85 biting the surfaces of the respective plate-members 7' and 7 preventing any accidental disarrangement of the said locking means when thus brought into locking or holding engagement. 90

As it may be desired to remove said head from its connection with said main body-portion 2 and its arm 5, the said head-piece of said pivot-stud 6 is provided with a pair of suitably disposed spanner-wrench receiving holes or depressions 24, by means of which said pivot-stud may be removed from its connection with said lock-nut member 19, and thus from its pivot-providing relation to said head and arm 5. The said main 100 body-portion 2 is further provided with diamond shaped perforations 25, the same being located opposite the main divisional points of the graduated scale 4. These perforations serve as a means for striking 105 arcs, circles or the like, since by inserting a sharp instrument, such as a bradawl, in one perforation and a pencil or marking instrument in another, the latter may be caused to strike the desired arc or circle. 110 The diamond-shaped perforation is provided since it provides a wedge-like edge or means for holding the instrument, no matter in which direction the movement of striking the arc or circle takes place, thus 115 firmly holding said instrument and insuring a mathematically correct arc or circle and an evenly described line indicating the same, free from waves or irregularities. 120

Referring now more particularly to Figs. 6 and 7 of the accompanying drawings, there is illustrated therein a slightly modified form of locking means for securing the head of the instrument in desired adjusted relation to the main body-portion. In the 125 said Figs. 6 and 7, the main body-portion is indicated by the reference-character 26, the arm connected therewith by the reference-character 27, and the respective plate-members forming the adjustable head by 130

the reference-characters 28 and 28', the general construction and related connection of said thus referred to parts being the same as hereinabove described in connection with the main or preferred construction of the 5 novel instrument comprising this invention. Said head is pivotally connected with said arm 27 by means of a pivot-stud 29 provided with a head-piece 30 the under surface 10 face 31 of which is suitably inclined. The shank of said pivot-stud 29 is provided with suitable screw-threads 32 whereby a nut-piece 33 is connected therewith, said nut-piece being cupped out or concaved on its under side, as at 34, thus providing at the 15 marginal edges of said nut-piece a sharp gripping edge 35 which contacts with the surface of said plate-member 28. Slidably arranged upon the surface of said plate-member 28' is a wedge-block or lock-piece 36, the same being provided with a slotted end or cut out portion 37 adapted to straddle said pivot-stud shank and thus permit said wedge-block or lock-piece to be introduced between said head-piece 30 of said pivot-stud 29 and said plate-member 28'. Pivotally mounted in connection with the head formed by said plate-members 28 and 28' by means of its journal-studs 38 is a 20 rotatable member 39 provided with an outwardly projecting arm 40. Pivotally connected with the free end of said arm 40 and connected in like manner at its opposite end with said wedge-block or lock-piece 36 is a 25 connecting link-member 41. Extending from said rotatable-member 39, in substantially an opposite direction to that of the arm 40, is a lever-arm 42 provided at its 30 free end with a turned-up finger-piece 43 for manipulating the same. As will be clearly understood from an inspection of Figs. 6 and 7 of the drawings, when said 35 rotatable member 39 is turned in a proper direction by the lever-arm 42, it tends to 40 straighten the toggle formed by the arm 40 and its connecting link-member 41, and thereby forces forward said wedge-block or lock-piece 36 which has the tendency to exert a pull upon said pivot-stud 29, binding in rigidly held or locked engagement 45 said nut-piece 33 and plate-member 28 and said wedge-block or lock-piece 36 and plate-member 28' with the free end of said arm 27, thus firmly locking the head in adjusted 50 relation to said main body-portion 26.

It will be clearly apparent, that the compound instrument above described is readily and quickly adjustable, and securely maintained in its adjusted positions, and that 55 the same is readily adapted to the performance of many functions and operations both in building and construction work, as well as in drafting and similar work.

I am aware that changes may be made in 60 the various arrangements and combinations

of the several parts without departing from the scope of my present invention. Hence, I do not limit my invention to the exact arrangements and combinations of the parts as herein described and as illustrated in the 70 accompanying drawings, nor do I confine myself to the exact details of the construction of the said parts.

I claim:—

1. A compound instrument comprising a 75 main body-portion provided with an angularly extending arm, an adjustable head pivotally connected with said arm and having its free end straddling said main body-portion, ribs projecting in opposite directions from the inner marginal edges of said head, and a rib projecting from the outer marginal edge of the under side of said head, said last-mentioned rib serving to position said instrument for use in connection 80 with a T-square, substantially as and for the purposes set forth.

2. A compound instrument comprising a main body-portion provided with an angularly extending arm, an adjustable head 90 pivotally connected with said arm and having its free end straddling said main body-portion, ribs projecting in opposite directions from the inner marginal edges of said head, and a rib projecting from the outer 95 marginal edge of the under side of said head, said last-mentioned rib serving to position said instrument for use in connection with a T-square, and locking means for securing said head in desired adjusted relation to said main body-portion and its angularly extending arm, substantially as and for the purposes set forth.

3. A compound instrument comprising a main body-portion provided with an angularly extending arm formed integral with said main body-portion at the one end thereof, and a head pivotally connected at one end with said arm, said head comprising a pair of plate-members registered one with 105 the other, an intermediate plate for securing said plate-members in spaced-apart relation to each other to provide intervening spaces between the ends of said plate-members so that one end of the latter will straddle said main body-portion in movable relation thereto and the other end will straddle said angularly extending arm in pivoted relation thereto, an outwardly extending 110 guide-rib connected with the inner marginal edge of the upper of said plate-members, an outwardly extending guide-rib connected with the inner marginal edge of the lower of said plate-members, and an outwardly extending guide-rib connected with the 115 outer marginal edge of said lower plate-member, said last-mentioned guide-rib serving to position said instrument for use in connection with a T-square, substantially as and for the purposes set forth.

4. A compound instrument comprising a main body-portion provided with an angularly extending arm formed integral with said main body-portion at the one end thereof, and a head pivotally connected at its one end with said arm, said head comprising a pair of plate-members superimposed and aligned one with the other, an intermediate plate for securing said plate-members in spaced-apart relation to each other to provide spaces between the ends of said plate-members so that one end of the head will straddle said main body-portion in movable relation thereto and the other end 10 will straddle said angularly extending arm in pivoted relation thereto, an outwardly extending guide-rib connected to and aligned with the inner marginal edge of the upper of said plate-members, an outwardly extending 15 guide-rib connected with the inner marginal edge of the lower of said plate-members, an outwardly extending guide-rib connected with the outer marginal edge of said lower plate-member, said last-mentioned 20 guide-rib serving to position said instrument for use in connection with a T-square, and locking means for securing said head in desired adjusted relation to said main body-portion and its angularly extending arm, 25 substantially as and for the purposes set forth.

5. A compound instrument comprising a main body-portion provided with an angularly extending arm formed integral with 30 said main body-portion at the one end thereof, and a head pivotally connected at its one end with said arm, said head comprising a pair of plate-members registered one with the other, an intermediate plate for securing 35 said plate-members in spaced-apart relation to each other to provide intervening spaces between the ends of said plate-members so that one end of the latter will straddle said main body-portion in movable relation thereto and the other end will straddle said angularly extending arm in pivoted relation thereto, an outwardly extending 40 guide-rib connected with the inner marginal edge of the lower of said plate-members, an outwardly extending guide rib connected with an outer marginal edge of said lower plate-member, said last-mentioned guide-rib serving to position said instrument for use in connection with a T-square, and means for 45 forcing the ends of said respective plate-members into rigid frictional holding engagement with said angularly extending arm to secure said head in desired adjusted relation to said main body-portion, substantially as and for the purposes set forth.

45 5. A compound instrument comprising a main body-portion provided with an angularly extending arm formed integral with said main body-portion at the one end thereof, and a head pivotally connected at its one end with said arm, said head comprising a pair of plate-members registered one with the other, an intermediate plate for securing said plate-members in spaced-apart relation to each other to provide intervening spaces between the ends of said plate-members so that one end of the latter will straddle said main body-portion in movable relation thereto and the other end will straddle said angularly extending arm in pivoted relation thereto, an outwardly extending guide-rib connected with the inner marginal edge of the upper of said plate-members, an outwardly extending guide-rib connected with the inner marginal edge of the lower of said plate-members, an outwardly extending guide rib connected with the outer marginal edge of said lower plate-member, said last-mentioned guide-rib serving to position said instrument for use in connection with a T-square, and locking means for securing said head in desired adjusted relation to said main body-portion and its angularly extending arm, comprising a screw-threaded pivot-stud, a head-piece connected with said pivot-stud, said head-piece being cupped out on its under side to provide a sharp marginal gripping edge engaging one of said plate-members, a nut-piece provided with an interiorly screw-threaded perforation adapted to receive said screw-threaded pivot-stud, said nut-piece being cupped out on its under side to provide a sharp marginal gripping edge engaging the other or opposite of said plate-members, and a lever-arm connected with said nut-piece for tightening or loosening the same to draw the ends of said respective plate-members into rigid frictional holding engagement with said angularly extending arm, substantially as and for the purposes set forth.

6. A compound instrument comprising a main body-portion provided with an angularly extending arm formed integral with said main body-portion at the one end thereof, and a head pivotally connected at its one end with said arm, said head comprising a pair of plate-members superimposed and aligned one with the other, an intermediate plate for securing said plate-members in spaced-apart relation to each other to provide intervening spaces between the ends of said plate-members so that one end of the latter will straddle said main body-portion in movable relation thereto and the other end will straddle said angularly extending arm in pivoted relation thereto, an outwardly extending 70 guide-rib connected with the inner marginal edge of the upper of said plate-members, an outwardly extending guide-rib connected with the inner marginal edge of the lower of said plate-members, an outwardly extending guide rib connected with an outer marginal edge of said lower plate-member, said last-mentioned guide-rib serving to position said instrument for use in connection with a T-square, and means for forcing the ends of said respective plate-members into rigid frictional holding engagement with said angularly extending arm to secure said head in desired adjusted relation to said main body-portion, substantially as and for the purposes set forth.

7. A compound instrument comprising a main body provided with an angularly extending arm, an adjustable head provided with one end adapted to straddle said arm in pivoted relation therewith and an opposite end adapted to straddle said main body-portion in slidable relation therewith, and means for forcing the first-mentioned straddling end of said head in rigid frictional holding engagement with said angularly extending arm to secure said head in desired adjusted relation to said main body-portion, comprising a screw-threaded pivot-stud, a head-piece connected with said pivot-stud, said head-piece being cupped out on its under side to provide a sharp marginal gripping edge engaging one side of said straddling end of said head, a nut-piece provided with an interiorly screw-threaded perforation adapted to receive said screw-threaded pivot-stud, said nut-piece being cupped out on its under side to provide a sharp marginal gripping edge engaging the other or opposite of said plate-members, and a lever-arm connected with said nut-piece for tightening or loosening the same to draw the ends of said respective plate-members into rigid frictional holding engagement with said angularly extending arm, substantially as and for the purposes set forth.

80 8. A compound instrument comprising a main body-portion provided with an angularly extending arm, an adjustable head provided with one end adapted to straddle said arm in pivoted relation therewith and an opposite end adapted to straddle said main body-portion in slidable relation therewith, and means for forcing the first-mentioned straddling end of said head in rigid frictional holding engagement with said angularly extending arm to secure said head in desired adjusted relation to said main body-portion, comprising a screw-threaded pivot-stud, a head-piece connected with said pivot-stud, said head-piece being cupped out on its under side to provide a sharp marginal gripping edge engaging one side of said straddling end of said head, a nut-piece provided with an interiorly screw-threaded perforation adapted to receive said screw-threaded pivot-stud, said nut-piece being cupped out on its under side to provide a sharp marginal gripping edge engaging the other or opposite of said plate-members, and a lever-arm connected with said nut-piece for tightening or loosening the same to draw the ends of said respective plate-members into rigid frictional holding engagement with said angularly extending arm, substantially as and for the purposes set forth.

under side to provide a sharp marginal gripping edge engaging the opposite side of said straddling end of said head, and a lever-arm connected with said nut-piece for manipulating the same.

In testimony, that I claim the invention

set forth above I have hereunto set my hand this 20th day of August 1912.

GEORGE F. HALL.
